UNITED STATES PATENT OFFICE.

MANGOLD H. ELLENBOGEN AND ABRAM L. LEVI, OF PATERSON, NEW JERSEY.

NECKBAND-SHAPER.

SPECIFICATION forming part of Letters Patent No. 701,181, dated May 27, 1902.

Application filed February 5, 1902. Serial No. 92,608. (No model.)

To all whom it may concern:

Be it known that we, MANGOLD H. ELLENBOGEN and ABRAM L. LEVI, citizens of the United States, and residents of Paterson, in 5 the county of Passaic and State of New Jersey, have invented a new and Improved Neckband-Shaper, of which the following is a full, clear, and exact description.

The invention relates to the laundering of shirts; and its object is to provide a new and improved neckband-shaper which is simple and durable in construction and readily adjustable to different-sized neckbands and conveniently applied to the neckbands to 5 hold the same in proper position during the ironing of the shirt-yoke to insure proper setting of the neckband and uniformity in the shape of the neckbands.

The invention consists of novel features 10 and parts and combinations of the same, as will be more fully described hereinafter and then pointed out in the claims.

A practical embodiment of the invention is represented in the accompanying drawings, 15 forming a part of this specification, in which similar characters of reference indicate corresponding parts in all the views.

Figure 1 is a perspective view of the improvement. Fig. 2 is a rear elevation of the 20 same, and Fig. 3 is a transverse section of the same.

The neckband-shaper consists, essentially, 25 of the members A and B, preferably made of spring sheet-metal bands and formed with curved front portions A' and B' and straight back portions A² B², as plainly indicated in Fig. 1. The front portions A' B' overlap each other, and on the free end of the outer portion B' is secured a loop C, through which extends 30 loosely the other portion A'. On the inside of the portion B' is secured a bolt D, extending inwardly through an elongated slot A³, formed in the free end of the portion A', and on the said bolt D screws a nut D', adapted 35 to engage the inner face of the portion A', the said bolt and nut forming a means for securely fastening the front portions A' and B' of the members A and B together after the 40 said members are adjusted to conform to the size of the neckband on which the shaper is to be used.

In order to permit proper and accurate adjustment of the members A and B according to the size of the neckband, the inner face of the front portion B' is provided with a linear 55 graduation E, on which slides the end edge of the portion A', said end edge indicating upon the graduation the size of the neckband that will fit the shaper, it being understood that when the said edge stands at 17.2 the 60 shaper is set for a neckband of seventeen and one-half inches in length. The corners A⁴ B⁴ of the members A and B are preferably rounded off to set the back portions A² and B² somewhat inwardly, as plainly shown in 65 Fig. 1, so that the rear end of the neckband stretches from one corner to the other without touching the back portions A² B².

The rear or back portions A² and B² are provided at their overlapping ends with 70 rigidly-attached loops F and F', normally abutting one against the other, of which the loop F forms a guideway for the portion B² and the other loop F' forms a similar guideway for the portion A². Now when the shaper 75 has been set to the size of the neckband and it is desired to place the shaper in position on the inner face of the neckband, then the operator presses the members toward each other at the rear ends, so that the straight back 80 portions A² and B² slide one over the other to reduce the size of the shaper, and thereby allow its convenient insertion in the neckband. When this has been done, the operator releases the members from pressure and the 85 members consequently open up, owing to their resiliency, until the loops F F' again abut one against the other. The neckband is now tightly stretched over the shaper.

In defining our invention with greater clearness we would state that the distinctive features are two main members, each of which comprehends a portion of the chord of a circle and a portion of the arc, the chord-sections having a slidable connection with each 90 other and the arc portions having also a slid- 95 able connection with each other, and one of said connections having means for rigidly locking it, and also graduations on one of the connecting parts and the other connection be- 100 ing free to slide, and the arc portions being also made as springs to permit a further in-

ward yielding of the chord-sections to permit compression for insertion into the neckband.

In practice the shaper is inserted in the neckband after the latter is ironed and previous to ironing the yoke or other parts adjacent to the neckband. Now by the use of the shaper the neckband is set to the shape of the shaper on ironing the yoke, it being understood that the operator need not pay any attention to the neckband while ironing around it, and hence can devote all his attention to the proper ironing of the yoke. It is understood that ironing the yoke sets the neckband firmly, and by the use of the device all the neckbands treated are set uniformly. After the shirt is ironed the operator removes the shaper from the neckband.

The device is very simple and durable in construction, is not liable to get out of order, and can be easily manipulated and adjusted in the manner above described and for the purpose set forth.

Having thus described our invention, we claim as new and desire to secure by Letters Patent—

1. A neckband-shaper comprising two separate members, each of which has one portion bent to form the chord of an arc and the other portion the circumference of the arc, the chord portions of the members being slidably connected and the arc portion being also slidably connected, and means for rigidly locking one of their sliding connections while the other remains yielding, substantially as 35 and for the purposes described.

2. A neckband-shaper comprising two sepa-

rate members, each of which has one portion bent to form the chord of an arc and the other portion the circumference of the arc, the chord portions having each a rigidly-attached 40 terminal keeper with the keeper of each chord-section embracing the body part of the opposite member, and a locking device for the sliding curved portions of the members, substantially as described. 45

3. A neckband-shaper comprising two separate members, each of which has one portion bent to form the chord of an arc and the other portion the circumference of the arc, and having also at the bend of these two portions a 50 rearwardly-extending offset A⁴ and B⁴, sliding connections for the chord portions, sliding connections for the arc portions, and means for locking one of said sliding connections to a rigid adjustment substantially as shown and 55 described.

4. A neckband-shaper comprising two members united to form a curved front and a straight back, the members having their back portions slidably connected and the front portions overlapping for adjustable attachment one to the other, and means for securing the front portions together, after the same have been adjusted, as set forth.

In testimony whereof we have signed our 65 names to this specification in the presence of two subscribing witnesses.

MANGOLD H. ELLENBOGEN.
ABRAM L. LEVI.
